UNITED STATES PATENT OFFICE.

MALCOLM GROVER ADAMS, OF PARSONS, KANSAS.

FLYING-MACHINE.

No. 917,513.

Specification of Letters Patent.

Patented April 6, 1909.

Application filed August 7, 1908. Serial No. 447,400.

To all whom it may concern:

Be it known that I, MALCOLM G. ADAMS, a citizen of the United States, and a resident of Parsons, in the county of Labette and State of Kansas, have invented a new and Improved Flying-Machine, of which the following is a full, clear, and exact description.

This invention relates to flying machines, and more particularly to an aeroplane or heavier-than-air flying machine, which comprises a plurality of superposed planes, preferably two in number, of which the upper one is movable relatively to the lower one, so that the fore and aft inclination of the upper one can be altered at will by the operator, and so that further, the upper plane can be twisted to alter the inclination of one end or the other to increase the lift or head resistance at the corresponding end of the machine to enable it to turn while flying, the machine having vanes tending to prevent skidding or lateral slipping when making a turn, and having the planes so curved that the machine will automatically tend to maintain its equilibrium, and substantially horizontal position when turning.

An object of the invention is to provide a simple, inexpensive and efficient heavier-than-air flying machine which can be driven by any suitable form of motor, which can be maneuvered readily while in the air, and which is at all times under the control of the operator.

A further object of the invention is to provide a machine of the class described, in which the controlling of the machine is effected by the movements of one or more of the upper planes, which are freely adjustable relatively to the lower plane, and which can be tilted and at the same time can be moved bodily forward with respect to the lower plane.

A still further object of the invention is to provide a machine of the class described comprising a plurality of superposed planes which are relatively movable with respect to one another and one of which can be adjusted to alter the head resistance as well as to alter the lift, in which the planes are concave, and in which they are provided with substantially vertical vanes at the ends to minimize side slip or skidding when the machine is making a turn.

Another object of the invention is to pro-

vide a heavier-than-air flying machine which has a suitable running gear, and in which the flight of the machine is controlled by the movements of the planes relative to one another, the operator controlling the movable planes by means of suitable mechanism, the operator further, assisting in balancing the machine, by moving his body forward or backward, or laterally, as the case may be.

The invention consists in the construction and combination of the parts to be more fully described hereinafter and particularly set forth in the claims.

Reference is to be had to the accompanying drawings forming a part of this specification, in which similar characters of reference indicate corresponding parts in all the views, and in which—

Figure 1 is a perspective view showing an embodiment of my invention; Fig. 2 is an end elevation of the flying machine; Fig. 3 is a diagrammatic end elevation showing the planes in certain relative positions; Fig. 4 is a view similar to Fig. 3, showing the planes in other relative positions; Fig. 5 is a perspective diagrammatic view of the form of the invention shown in Fig. 1; Fig. 6 is a diagrammatic, perspective view showing a modified form of the invention; Fig. 7 is a diagrammatic end elevation showing a further modified form of the invention; Fig. 8 is a similar view showing a still further modified form of the flying machine; Fig. 9 is a diagrammatic, end elevation showing another modified form of the invention; and Fig. 10 is a similar view showing still another modified form of the device.

Before proceeding to a more detailed explanation of my invention it should be clearly understood that while I have shown in the accompanying drawings, various types of flying machines each of which comprises two superposed planes, I can also employ a greater number of superposed planes if so desired. In the form of the device shown, the upper plane is movable relatively to the lower plane and the control in flight, of the machine, is effected by the movements and adjustments of the upper plane. In Fig. 1 I have shown one embodiment of the flying machine in which the upper plane comprises two sections which are movable relatively to the lower plane and to each other. In Fig. 6 is shown a form in which the upper plane

comprises a single section and in which this section can be twisted so that its opposite ends are movable relatively to one another as are the separate sections of the upper plane shown in Fig. 1. In effect, the result is the same and the head resistance and lift can be altered at one end of the machine or the other, as desired, by the operator. I prefer to arrange the upper plane upon link uprights or supports which permit the upper plane to be moved forward or backward bodily with respect to the lower plane. The forward or backward bodily movements of the upper plane at the same time cause it to tilt, owing to the provision of the link uprights. In this way, the head resistance of the upper plane, and consequently, of the entire machine is varied. At the same time, one end can be tilted one way or the other to vary the head resistance on the corresponding end, to cause the machine to turn as will appear more clearly hereinafter. Referring more particularly to the drawings, I provide a lower plane A and an upper plane B. The plane A comprises transverse members 11 and 11* and end members 12 connecting the extremities of the transverse frame members. Intermediate the end frame members 12 are other longitudinal frame members 13 and 14. The frame members may consist of any suitable material such as light metal tubing, bamboo, wood or the like, and may be secured together in any convenient manner, for example, by binding tightly with strong wire, or by providing special sockets or brackets for the purpose. The surface of the plane consists of a covering 15 of light sheet metal, fabric or any other suitable material which may be secured to the frame members in any convenient manner. The longitudinal frame members 14 are spaced apart and the space therebetween is not covered with the surface 15 but is left open so that a supporting bar 16 can be arranged therebetween. The latter has the ends secured to the transverse members 11 and carries a suitable seat 17 upon which the operator may assume his position. The lower plane is strengthened by diagonal and other braces or guys 18 extending across the plane and secured at the ends or intersections of the frame members. The braces consist preferably of strong wires or the like. Shoulder straps 19 are secured to the supporting bar 16 so that the operator can partly support the weight of the machine before starting the flight. A foot rest 20 is fastened at the front transverse frame member and consists of a cross bar 21 secured at the lower ends of hangers 22 depending from the front transverse member 11. The foot rest is strengthened with diagonal wire braces 23 and is secured to the longitudinal frame members 14 by means of the members 24.

The longitudinal frame members 13 have bifurcated supports 25 slidably mounted in openings thereof. Helical springs 26 are mounted upon the shanks 27 of the supports and engage at the crowns and the fore and aft frame members 13. Supporting wheels 28 which may be of any suitable form are mounted between the sides of the forks and serve to permit the flying machine to be run along the ground. Forks 29 have the shanks pivotally secured to the members 13 and further have the extremities of their sides engaging at the hubs of the wheels 28. The forks 29 serve to brace the wheels, while permitting the same to move toward the lower plane. The springs 27 absorb the shocks and jars incident to moving the machine over rough ground or roads.

In the form shown in Fig. 1, the upper plane B comprises separate sections B' and B* each of which has transverse members 30 and 30*, end members 31 and longitudinal members 32. The frame members of the upper plane are covered with a fabric or other surface 33 and have diagonal bracing guys or wires 34. The latter include helical or other spring sections 35 which, while tending to maintain the plane sections in normal positions, permit the same to alter their forms under the adjustment to which they are subject. The upper plane sections are supported upon the lower plane by link uprights 36 which consist of rods of suitable material having the upper and lower ends pivoted respectively to the end frame members or the longitudinal frame members of the plane. The link uprights are preferably pivoted at their lower ends at the extremities of the frame members of the lower plane and at their upper end intermediate the extremities of the frame members of the upper plane sections, as appears most clearly in Fig. 2. Consequently the link uprights are normally inclined toward each other. It will be understood that this construction permits the upper plane or the upper plane sections to be moved freely relative to the lower plane, that is to be moved freely backward and forward. Owing to the provision of the link uprights, the backward or forward movement at the same time tilts the upper plane and thus alters the fore and aft inclination and the head resistance of the upper plane. The link uprights are held against lateral movement by braces or guys 52, consisting of wires or the like and including springs 53 which permit the braces to adjust themselves slightly to strains. The braces 52 are in the same planes as the link uprights and permit the same to swing freely in a fore and aft direction while holding them securely against lateral movement.

A controlling bar 37 is arranged transversely of the supporting bar 16 and has the ends secured by means of rods 38 to the

upper plane sections B' and B². If a single upper plane is employed the ends of the controlling bar are connected to the upper plane near the respective ends of the same. 5 Each end of the controlling bar has the rods 38 running respectively, to the front and the back of the upper plane. By means of the bar which is located conveniently close to the operator's seat 17, the upper plane or 10 plane sections can be easily controlled; that is, can be moved backward or forward and tilted as desired.

Strong helical or other springs 39 are secured to certain of the link uprights 36 15 and the upper plane or plane sections adjacent to others of the link uprights. This arrangement tends to hold the upper plane in a normal position with respect to the lower plane and any adjustment of the upper 20 plane can be made against the tension of the springs 39.

Upon the lower plane is arranged a frame work which consists of a top frame member 40 supported on inclined struts 41, running 25 from the ends of the longitudinal frame members of the lower plane. The cross section of this frame-work is substantially triangular and cross bars 42 connect the struts 41 near the lower ends. Triangular 30 vanes or surfaces 43 are stretched upon the struts 41 and the cross bars 42. These vanes tend to steady the machine in the air and as they are substantially vertical, act to prevent slip or skidding when the machine is 35 making a turn. The frame is strengthened by suitable braces 42^a including the springs 43^a which allow for slight movements and adjustments of the frame members.

At the ends of the upper and lower planes 40 are downwardly extending posts 44 braced by means of inclined members 45. Bottom members 46 connect the lower ends of the posts 44 and have the rear ends upwardly curved to the end frame members of the 45 planes. Vanes or surfaces 47 of fabric or other suitable material are stretched over the posts and the bottom members and form end vanes or wings which tend to prevent side slipping or skidding when the machine 50 is turning.

At the rear of the lower plane preferably upon the longitudinal members 14 is arranged a supporting frame work 48 which carries a motor 49 of any suitable type. The 55 shaft 50 of the motor extends rearwardly from the same and carries the driving propeller 51. The latter may be of any preferred or common type.

It will be understood that the constructive details shown for example, herewith, can be altered in accordance with individual preference and special conditions, without departing from the underlying spirit of the invention. Furthermore, any suitable materials can be employed and the mode of

strengthening, bracing, or attaching the parts can be varied as necessary.

It should be noted that the planes are concave, and I prefer that this should be the case, as there is a tendency with this form, 70 for that side of the machine to rise which is at the inside of the turn when the machine is traveling on a curve. This action is due to the fact that the lateral or side movement of the machine—that is, the slipping or 75 skidding—is caused by centrifugal action, and that the portions of the planes nearer to the direction of the turning have greater inclination to the actual line of motion than do the sides farther from it. Consequently, 80 the side nearer tends to rise, as the inclination of the planes of course, controls the upward or downward movement of the machine. Furthermore, the provision of the vertical vanes at the ends of the planes 85 assists in the control of the machine, as the vane farther from the direction of turning will hold the air under it, while the other one will shield a portion of the plane and thus decrease the lift on that side, in opposition to the increased lift at the other end. 90 These actions are of advantage, as the machine tends to lose its balance and lean to one side or the other in making a turn.

In the form of the machine shown in 95 Fig. 6, the upper plane B comprises a single section, and the ends of the single section, which is sufficiently flexible to permit the plane to be twisted, can be raised or lowered independently of one another by distorting 100 the upper plane. In this manner the same effect is produced as by the movements of the plane sections B' and B² relative to one another.

In Fig. 7 is shown a modified form in 105 which the upper plane B is pivotally mounted upon inverted V-shaped supports C, and in which the upper plane is pivotally movable along a line transverse of the plane. In this type, the controlling bar 37 and the 110 rods 38 are the same as in the other forms.

In Fig. 8 is shown a further modified form in which two inverted V-shaped supports C' and C² are employed to carry the upper plane B. The latter comprises a front portion B⁴ and a rear portion B³. These are pivotally movable independently of one another and are controlled by a frame D connected by means of rods D' and D² with the sections B³ and B⁴ respectively, of the upper 115 plane. By moving the frame D in one direction, the section B³ is tilted downward, and the section B⁴ is simultaneously tilted upward, so that the effect is the same as if the entire frame were tilted. A movement 120 of the frame D in an opposite direction reverses the inclinations of the sections B³ and B⁴.

In the forms of the flying machine shown in Figs. 9 and 10 I provide a series of invert- 125

ed V-shaped supports C as in the form shown in Fig. 7, and further inverted V-shaped supports C³, one of the members of each of the latter is substantially vertical. The supports C and C³ carry an upper plane B³ which is held substantially immovable with respect to the lower plane A. A further movable upper section B⁶ is pivotally mounted at the apexes of the supports C and is controlled by the bars 37 of the rods 38. The two forms of the machine are quite similar, with the exception that in one case the movable plane section B⁶ is at the front of the machine, while in the other case it is at the rear.

I wish to emphasize that the operation of my flying machine depends almost entirely upon the fore and aft inclination of the upper plane or plane sections, and that the latter are not tilted or inclined laterally or transversely of the machine in any way. In steering and balancing, the respective top plane sections, or the respective ends of the single top plane, are tilted or inclined, or twisted relatively to one another so that the lift and the head resistance at one end of the machine differ from that of the other. By increasing the head resistance of the one end, the machine is caused to turn in a corresponding direction. By uniformly altering the inclination of the upper plane, the machine can be caused to rise or fall. The following is an example of the manner in which the machine can be balanced: If for some cause or other the machine leans to the right, the operator will move the right end of the controlling bar ahead, thus tilting the right top plane section or end, and thereby increasing the fore and aft inclination of the same on the right side only. The lift will be increased on the right side and thus the balance of the machine will be recovered; but, at the same time the increased head resistance of the right side will cause the machine to turn to the right, and the centrifugal force will cause the machine to skid or slide to the left. The function of the concavity of the planes together with the vertical vanes at the ends of the planes or intermediate the ends, is to assist in restoring the lateral or transverse balance as has been stated above.

If it is desired to cause the machine to turn, say to the right, the top plane at the right is tilted to increase the head resistance at that side. This increase in the resistance and the lift will tend to overbalance the machine so that the operator will lean his body toward the right side in making a turn to the right. The steering and lateral balancing of the machine will be not unlike the steering and balancing of a bicycle or similar device, inasmuch as the operator leans toward the direction in which the turn is made, and also turns in the same direction in which he

leans when he loses his balance. By tilting the top aeroplane backward or forward the machine can be caused to descend or ascend, as well as to be balanced in a fore and aft direction. The operator can lean his body forward or backward in case of necessity to assist in holding the fore and aft balance.

Having thus described my invention, I claim as new, and desire to secure by Letters Patent:

1. In a flying machine, a plurality of planes, and means for simultaneously tilting and moving bodily, one of said planes with respect to the other. 75
2. In a flying machine, a plurality of superposed planes, and pivoted links for connecting said planes whereby the same are movable relative to one another, and whereby their relative inclinations can be varied. 80
3. In a flying machine, a plurality of superposed planes, links for operatively connecting said planes whereby the same are movable relatively to one another, and adjustable rods for controlling one of said planes, whereby the same can be simultaneously tilted and moved bodily. 85
4. In a flying machine, a plurality of superposed planes, means for operatively connecting said planes whereby the same are movable relatively to one another, and 90 means for controlling one of said planes whereby the same can be simultaneously tilted and moved bodily. 95
5. In a flying machine, a plane arranged to swing in a fore and aft direction, and means for simultaneously tilting and twisting said plane. 100
6. In a flying machine, a plurality of superposed planes, one of said planes consisting of separated sections movable relatively to 105 one another, and a link connection between each of said sections and said other plane.
7. In a flying machine, a plurality of superposed planes, one of said planes comprising independently movable sections, and 110 means for simultaneously tilting and moving bodily each of said sections independently of the other.
8. In a flying machine, a plurality of superposed planes, a link connection between 115 said planes whereby the upper of said planes is adapted to swing relatively to said lower plane in a fore and aft direction, and means for controlling said upper plane whereby the same can be simultaneously tilted and 120 moved bodily.
9. In a flying machine, a plurality of superposed planes, links connecting said planes whereby the same are free to move relative to one another in a fore and aft direction, 125 means for adjusting one of said planes relatively to the other, and means tending to hold one of said planes in a normal position relative to the other of said planes.
10. In a flying machine, a plurality of su- 130

- perposed planes, one of said planes being movable in a plurality of directions relative to the other, and means tending resiliently to hold said movable plane in a normal position. 5
11. In a flying machine, a plurality of superposed planes, means for operatively connecting said planes whereby the same are movable relatively to one another in a plurality of directions, means tending to hold one of said planes in a normal position relative to the other of said planes, and means for controlling one of said planes whereby the same can be simultaneously tilted and moved bodily relatively to the other. 10
12. In a flying machine, a lower plane, an upper plane, links connecting said planes whereby said upper plane can be tilted and moved bodily with respect to said lower plane, means tending to hold said upper plane in a normal position relative to said lower plane, means for controlling said upper plane, and vanes at angles with said planes. 15
13. In a flying machine, a plurality of superposed downwardly concave planes having vanes at the ends thereof, said vanes being at substantially right angles to said planes, links connecting said planes whereby the same are movable relatively to one another in a fore and aft direction, and adjustable bars for controlling one of said planes whereby the same can be simultaneously tilted and moved bodily. 20
14. In a flying machine, a plurality of superposed, downwardly concave planes having vanes at the ends thereof, said vanes being at substantially right angles to said planes, means connecting said planes whereby the same are movable relatively to one another in a fore and aft direction, and means for controlling one of said planes whereby the same can be simultaneously tilted and moved bodily. 25
15. In a flying machine, a plurality of superposed planes movable relatively to one another in a fore and aft direction, and braced against movement transversely of one another. 30
16. In a flying machine, a plurality of superposed planes, links connecting said planes whereby the same are movable relatively to one another in a fore and aft direction, and guys connecting said links and one of said planes whereby said links are held against movement in a direction transverse of the machine. 35
17. In a flying machine, a plurality of superposed, concave planes having vanes at the ends thereof and extending at angles to said planes, means for operatively connecting said planes whereby the same are movable relatively to one another in a fore and aft direction and are held against movement relative to one another in a transverse direction, means for normally holding said planes in normal positions relative to one another, and means for adjusting one of said planes whereby the same can be moved relatively to the other. 40
18. In a flying machine, a plane comprising frame members, a covering for said frame members, and braces connecting said frame members, said braces being extensible. 45
19. In a flying machine, a plane comprising frame members, a covering supported upon said frame members, and braces connecting said frame members and having resilient portions. 50
20. In a flying machine, a plane comprising longitudinal frame members and transverse frame members, a covering supported upon said frame members, and braces connecting said frame members and at angles therewith, said braces each having a portion constituting a spring. 55
21. In a flying machine, an upper plane and a lower plane, means for movably connecting said planes, and a frame rigidly supported upon said lower plane, said frame carrying vanes at angles with said planes. 60
22. In a flying machine, an upper plane, a lower plane, means for connecting said planes whereby the same are relatively movable, a frame mounted upon said lower plane and comprising a top frame member and pairs of struts supporting the same, said struts of each portion being at an angle with each other, and vanes supported by said struts. 65
23. In a flying machine, an upper plane, a lower plane, links movably connecting said upper plane and said lower plane, means for resiliently holding said planes in normal relative positions, a frame supported upon said lower plane and comprising a top frame member, and pairs of struts supporting the same, said struts of each pair being at an angle with each other, and vanes supported by said struts. 70
24. In a flying machine, a plurality of superposed planes, links for operatively connecting said planes whereby the same are movable relatively to one another, a manually adjustable member for controlling one of said planes whereby the same can be simultaneously tilted and moved bodily, and a propeller for advancing the machine in the air. 75
25. In a flying machine, a plurality of superposed planes, means for operatively connecting said planes whereby the same are movable relatively to one another, means for controlling one of said planes whereby the same can be simultaneously tilted and moved bodily, and means for advancing the machine through the air. 80
26. In a flying machine, a plurality of superposed planes, one of said planes having spaced sections movable relatively to one another, a prime mover movably supported 85

upon one of said planes, and means operable by said prime mover for advancing the machine through the air.

27. In a flying machine, a plurality of superposed planes, a link connection between said planes whereby one of the same can be tilted and moved bodily relatively to the other, means for supporting an operator upon one of said planes, a frame, a prime

mover supported upon said frame, and a propeller operable by said prime mover.

In testimony whereof I have signed my name to this specification in the presence of two subscribing witnesses.
